BENCH VISE

Hans Olsen, Everett, Wash.

Application August 18, 1937, Serial No. 159,696

4 Claims. (Cl. 81—33)

This invention relates to vises, and particularly to vises with a movable jaw, operated both manually and by motor power.

In the use of bench vises, much delay is frequently occasioned by the ordinary slow method of manually revolving a power screw for opening and closing the movable jaw. Attempts have been made to operate such screws by motor power, but in such attempts, the alternate use of hand power has been prevented by the rigid connection between the screw and jaw, which has been necessary to prevent the screw turning within the jaw when power was applied for turning a nut thereon for operating the screw. Attempts to use motor power, have usually failed to bind the jaws together sufficiently to hold articles between the same against the ordinary strains from work thereon. In cases where the jaws have been sufficiently bound together to hold the articles to be worked upon, then the resistance against opening the jaws, has been too great to be overcome by power means properly applied for clamping the jaws together.

In the use of a hand lever for operating the jaws, it is usual to turn the power screw within a fixed nut threaded thereover. In the use of a motor power it has been usual to affix the screw rigidly to the movable jaw and to turn a nut over the thread of the screw of the travelling jaw. Unless the screw is retarded from easy operation in the jaw, the screw will revolve with the nut when motor power is applied, and unless the nut is restrained when hand power is used, then the nut turns with the screw. In either case the jaw is not moved. It is therefore an object of this invention, to provide for both motor power and hand power, and to provide retarding means to prevent the nut from turning when the hand power is applied to the screw, and to provide retarding means to prevent the screw from turning when the nut is revolved by motor power.

It is a further object of the invention to provide both motor power means for driving the screw for rapidly opening and closing the loose jaw of the device, and also to provide means for hand operation of the screw for tightening the jaws rigidly against an object between the same, and for loosening the jaws from such article, and for using the motor power when the jaw has been so released. A still further object is to provide a tubular leg projection beneath the fixed jaw, for guiding a spindle for rotating the screw nut, and also adapted for a swivel connection to the bench, for the rotation of the vise thereon, together with means for holding the vise in various posi-

tions on the bench while the motor power may be applied in all such various positions of the vise.

With these and other objects to be hereinafter shown, I have illustratively exemplified my invention by the accompanying drawing, of which:

Figure 1 represents a side elevation of the vise mostly in section.

Figure 2 is an end view reduced in size, partly in section, taken on meandering line 2—2 of Figure 1, showing the power means.

Figure 3 is a top plan of parts of the vise, taken on meandering line 3—3 of Figure 1, partly in section and reduced in size.

Figure 4 is a perspective view of a form of spring washer for the spindle and screw, enlarged.

Like numerals and characters on the different figures represent like parts.

Numerals 5, represents the fixed jaw on a frame 5' and flange 6, which is mounted on any suitable work bench 7. 8 represents the loose or travelling jaw, which is supported on a horizontal rectangular tenon or arm 9, which is slidably disposed in a slot or mortice 10 through the frame of the fixed jaw.

An actuating screw 11 is rotatably mounted through the base of the travelling jaw and protrudes through a tubular passageway 12, of the arm, which is open at the bottom. A shoulder abutment 13, on the screw outside the jaw 8 and a resilient abutment or washer 14, around the screw and bearing on cheek 14' of the jaw 8, to move the jaw 8 to or from the fixed jaw as the screw is turned by hand lever 16. An elongated power nut 17 is threaded over the screw 11, and rotatably mounted through a post 18, which is projected up into the passageway and supported on a shoulder 19 of the frame. The turning of nut 17, upon the screw, or the turning of the screw within the nut, forces the jaw 8 to or from jaw 5 respectively.

Projected downward from and preferably integral with, the post is a tubular leg 20, which may be positioned through any suitable hole as 21 in the bench, and pivotally maintains the vise on the bench. The leg is tubular, and provides a journal bearing for an operative spindle 26, rotatably mounted therethrough. The nut 17 carries a rear extension 22, and a central enlarged collar with bevelled gear teeth 23 on the outer edge, and a flat opposite face 24, which bears against the rear side of the post 18, for a fulcrum for drawing the jaw 8 inward. A toothed pinion 25 is attached on the top end of the spindle as by a screw 26, and the base 1 of the pinion, is rotatably mounted on the top of the leg member.

The spindle 26, is extended below the leg, for any desired distance and carries pulley 27, on the end thereof. This pulley is turned in either desired direction by a belt 28, driven by any ordinary reversible electric motor indicated as 29, with an operating pulley 30. A resilient member or spring washer or abutment 31, is slidably mounted around the spindle beneath the leg, and retained in position against the same by ordinary jamb nuts 32. The nuts 32 are adjusted against the washer 31 with sufficient pressure to cause the washer to resiliently bind against the leg and to retard the spindle and pinion from turning, sufficiently to prevent the nut 17 from revolving when the power screw 11, is revolved by the hand lever 16; but to yet permit the spindle to be rotated without undue resistance when the belt is rotated by the motor for operating the nut 17.

In similar manner the resilient washer 14 mounted around the power screw adjacent to cheek 14', is adjustably tightened by jamb nuts 15, to prevent the screw 11 from turning when the power nut is revolved by the motor, but is so adjusted that the screw may be manually operated by the lever 16. Thus the operator may select either method of moving the jaw 8, and may preferably use the motor for rapidly moving the jaw for considerable distances, to close the jaws, and then use the lever for sufficiently 30 clamping any article between the jaws for work thereon. When the jaws are to be opened, they may be loosened by hand, and then opened by the motor. A stop pin 36 is provided across the rear end of the tenon, which prevents the jaw 8, 35 from being carried outward to disengage the screw 11 from the nut 17 after the pin strikes against the bar 33. The spring members 14 and 31, are similar, as shown enlarged in Fig. 4, and are provided with resilient lips a, alternately with notches b, and are slidably and rotatably positioned by means of the central eye c; over the 40 spindle or screw respectively.

The leg 29, through the hole in the branch, permits the vise to be swung in various lateral positions, which are frequently required by workmen for various kinds of work and materials, as indicated by dotted lines in Fig. 3. Meanwhile the perpendicular position remains unchanged, and so continues the spindle in alinement for 45 operation by the motor in all such various positions of the vise. The flange 6, is provided with any suitable number of holes therein as 37 for pins 38, which may be dropped down into suitable registering holes 38 in the bench, to prevent 50 lateral movement of the flange. On the lower portion of the leg is preferably mounted a hand wheel nut 40, over inner, and outside threads 41, and 42, respectively whereby the vise may be rigidly clamped upon the bench by the tightening of the wheel nut 40.

In order to revolve the spindle in either desired direction for opening or closing the jaw 8, a double ended lever 43 is mounted centrally over an ordinary double acting electric switch 65 (not shown) in a housing 44. Springs 45 beneath the opposite ends of the lever retain the same normally level, and the switch neutral. Ordinary electric wires for the reverse currents, are carried from the motor to the switch by a cable 46. 70 This switch and lever 43 may be positioned as indicated on the floor at any desired distance from the motor for operation by the feet of the user, or they may be attached above or beneath the bench for hand control. In either 75 case, the operator may use the motor for any

portion of the movements of the jaw 8, by pressure on respective end of the lever desired to rotate the spindle in the desired direction. On release of the pressure, the springs 45 throw the lever and switch into neutral position, and the spindle is immediately stopped by resistance from resilient member 31.

A bar 33 is seated in the rear edge of the leg and attached as by screw 34. The top of the bar is projected up and behind the rear extension 22, of the nut 17, and serves as a position bearing therefor. A set screw 35 provides suitable tension against the rear portion of the bar to maintain the nut in position.

In use the vise is mounted upon any suitable 15 bench or platform, with the leg and spindle extended beneath the same for operative connection with the motor, as described. In practice it is generally advisable to use the hand lever 16 for turning the screw 11, to finally tighten the 20 jaws upon any article to be held between the same; and when the jaws are to be loosened from such article, it is generally necessary to use the hand lever therefor. After the jaws have been loosened and it is desired to separate or open 25 the jaws a considerable space apart, or when it is desired to bring the same together when widely separated, then the motor is preferably applied. Thus the nut is rapidly turned over the screw and the loose jaw rapidly moved to or from the 30 fixed jaw, without loss of time. The resilient member 14 provides sufficient friction to prevent the screw from turning when the nut is operated by the motor; and the resilient member 31 provides sufficient friction to prevent the 35 spindle 26, the pinion thereon 25, and the said nut from turning when the screw is operated by the hand lever 16.

By the use of this vise and its means of operation, the operator may quickly, and without 40 changing his position before the same, have the advantages of slow hand power for severe tension, and also have the use of the motor drive for rapid movement of the loose jaw.

Having described my invention I claim as new:

1. A vise for cooperative motor and hand power comprising a fixed jaw on a frame, a loose jaw with a tubular arm slidably mounted through said frame, a power screw rotatably disposed through said loose jaw, a post mounted in the arm, a power nut rotatably mounted through the post, a tubular leg projected downward from the post for pivotally maintaining the vise on a bench and for a guide for a spindle, a driving spindle rotatably mounted through the leg, a collar around the power nut with gear teeth thereon, a pinion affixed to the top of the spindle with teeth in mesh with the gear for rotating said power nut over said screw for moving said loose jaw, a pulley on the lower end of said spindle and motor power means for driving the pulley in alternate directions for rapidly operating the spindle and loose jaw, and means for reversing the motor, resilient means carried on the screw for restraining the screw from turning when said nut is rotated thereon, and resilient means on the spindle for restraining such spindle and said nut from turning when said screw is rotated in the nut with means for manually turning the screw slowly for clamping and loosening said jaw.

2. A vise for hand and motor power use, comprising, a fixed jaw and a loose jaw, a screw for operating said loose jaw, a power nut rotatably mounted on said screw and adapted to be turned thereon for moving said screw and loose jaw lat-

erally, resilient means mounted on said screw to restrain the movement thereof sufficiently for the turning of said nut thereon, a spindle and a gear for rotating said nut rapidly by motor power, resilient means carried on said spindle to restrain the movement of said spindle and nut sufficiently for the turning of the screw within said nut for alternately moving said loose jaw slowly by hand power for accurate adjustment of the jaws together, and for separating the same, with means for separately turning said screw and said nut.

3. A vise with a fixed jaw on a frame and a movable jaw on a tubular arm slidably mounted through said frame, a power screw rotatably connected through said movable jaw and projected through said arm, a power nut rotatably mounted within said arm but independently thereof and in mesh with the screw for rotation thereon, a tubular leg extended downward from said frame for pivotal connection with the bench and to permit the vise to be swung in various directions along with said leg and for journal

bearing for a driving spindle mounted therethrough, gear teeth around the power nut, a driving pinion on the top of said spindle with teeth thereon in mesh with said gear, for rotating said nut, a pulley attached to the lower end of said spindle for continuous rotation of the same, while the position of the vise about the pivot may vary, with means for rotating said nut for propelling said movable jaw toward and away from said fixed jaw thereby, and means for reversing the direction of travel of said pulley together with resilient means for locking the screw when the power operated means is being used, and means for locking said nut when said screw is being used.

4. A vise with parts described in the foregoing claim 3 and provided with a shoulder on the top of said leg, extended over said frame, a thread around the lower portion of said leg, a hand wheel nut in mesh with said thread and adapted to bind said vise frame rigidly upon a bench in various positions in relation to said leg.

HANS OLSEN.
